US00D994597S

(12) **United States Design Patent** (10) Patent No.: **US D994,597 S**
(45) Date of Patent: ** Aug. 8, 2023

(54) **CHARGER**

- (71) Applicant: **Galvani Bioelectronics Limited**,
Middlesex (GB)
- (72) Inventors: **Jay Canham**, Brentford Middlesex (GB); **David Lari**, Brentford Middlesex (GB); **Cindy Au**, Brentford Middlesex (GB); **Melissa Lara**, Brentford Middlesex (GB); **Daniel Nobre**, Brentford Middlesex (GB); **Ryan Jongwoo Choi**, Brentford Middlesex (GB)
- (73) Assignee: **Galvani Bioelectronics Limited**,
Middlesex (GB)
- (**) Term: **15 Years**
- (21) Appl. No.: **29/826,951**
- (22) Filed: **Feb. 16, 2022**

CLAIM

The ornamental design for a charger, as shown and described.

DESCRIPTION

FIG. 1 is a top perspective view of a charger;
FIG. 2 is a bottom perspective view thereof;
FIG. 3 is top plan view thereof;
FIG. 4 is a bottom plan view thereof;
FIG. 5 is a front elevation view thereof;
FIG. 6 is a right side elevation view thereof;
FIG. 7 is a left side elevation view thereof; and,
FIG. 8 is a rear elevation view thereof.

The broken lines in the drawings are for the purpose of illustrating portions of the charger that form no part of the claimed design.

1 Claim, 8 Drawing Sheets
